CLAIM

The ornamental design for wireless controller for electronic shelf label as shown and described.

DESCRIPTION

1. Wireless controller for electronic shelf label

1.1 : Front

1.2 : Back

1.3 : Left

1.4 : Right

1.5 : Top

1.6 : Bottom

1.7 : Perspective view

The wireless controller is used for signal transmission and data processing for electronic shelf label.

The broken lines depict portions of the wireless controller for electronic shelf label that form no part of the claimed design.

1 Claim, 7 Drawing Sheets
